(57) CLAIM

The ornamental design for an armoire, as shown and described.

DESCRIPTION

FIG. 1 is a left front perspective view of an armoire showing my new design;

FIG. 2 is a side elevational view, the opposite side being a mirror image thereof; and,

FIG. 3 is a front elevational view thereof.

The dashed lines represent environmental elements only and form no part of the claimed design.
